US00D487071S

(12) **United States Design Patent** (10) Patent No.: **US D487,071 S**
Hotta et al. (45) Date of Patent: **** Feb. 24, 2004**

(54) **MOBILE PHONE**

(75) Inventors: **Mihoko Hotta, Kawasaki (JP);
Takayuki Miyazawa, Zushi (JP);
Takahiro Iijima, Tokyo (JP)**

(73) Assignee: **Matsushita Electric Industrial Co.,
Ltd., Osaka (JP)**

(**) Term: **14 Years**

(21) Appl. No.: **29/183,851**

(22) Filed: **Jun. 17, 2003**

(51) LOC (7) Cl. **14-03**

(52) U.S. Cl. **D14/138**

(58) Field of Search **D14/137, 138,
D14/218, 147-148, 247-248, 144, 341-347;

(57) **CLAIM**

The ornamental design for a mobile phone, as shown and described.

DESCRIPTION

FIG. 1 is a perspective view of a mobile phone of the present invention in an open position;

FIG. 2 is a front view thereof;

FIG. 3 is a first side view thereof;

FIG. 4 is a second side view thereof;

FIG. 5 is a rear view thereof;

FIG. 6 is a top view thereof;

FIG. 7 is a bottom view thereof; and,

FIG. 8 is a top perspective view thereof, wherein the mobile phone is in a closed position.
